(57) **CLAIM**

The ornamental design for a connector, as shown and described.

DESCRIPTION

FIG. 1 is a front elevation view of a connector of the present invention showing my new design;

FIG. 2 is a back elevation view thereof;

FIG. 3 is a top plan view thereof;

FIG. 4 is a bottom plan view thereof;

FIG. 5 is a right side elevation view thereof, the left side elevation view being a mirror image thereof;

FIG. 6 is an enlarged cross-sectional view thereof, taken along line 6—6 in FIG. 3;

FIG. 7 is a top, front, and right side perspective view thereof, showing a state before connection to a mating connector; and,

FIG. 8 is a top, front, and right side perspective view thereof. The broken line showing of the environment is for illustrative purposes only and forms no part of the claimed design.
